C. E. GOODYEAR

LAMP SUITABLE FOR USE ON VEHICLES

Filed Sept. 3, 1924

UNITED STATES PATENT OFFICE.

CLAUDE E. GOODYEAR, OF KIDDERMINSTER, ENGLAND.

LAMP SUITABLE FOR USE ON VEHICLES.

Application filed September 3, 1924. Serial No. 735,607.

To all whom it may concern:

Be it known that I, CLAUDE EUGENE GOODYEAR, a subject of the King of Great Britain, residing at Comberton Hall, Kidderminster, 5 in the county of Worcester, England, have invented certain new and useful Improvements in or Relating to Lamps Suitable for Use on Vehicles, of which the following is a specification.

10 This invention, which comprises certain improvements in or relating to lamps suitable for use on vehicles and to the manufacture of the same, is an improvement in or a modification of the invention forming 15 subject of my prior application Serial No. 606,256 of December 11th, 1922.

The invention of my said prior application relates to the type of lamp wherein a lamp-body, closed at the front, is composed 20 mainly or essentially of glass or other vitreous or ceramic material, and my said prior invention comprehends a lamp of this type upon the body of which an armouring has been deposited as, for instance, by electro- 25 deposition, the said armouring being of a character such that it is adapted substantially to avoid danger accruing as a result of flying splinters in the event of the lamp body being shattered or broken as a result of 30 impact.

The present invention comprehends an embodiment of my prior invention, wherein the lamp-body is integrally closed at the front and in which the armouring is continued around this front in the form of a marginal flange or inturned rim adapted to function as an abutment serving to prevent rearward derangement of the armouring.

35 The armouring may also be carried to the rear of the lamp-body at which the opening for the accommodation of the lamp holder may be provided, and at this point the armouring may also be provided with an inward flange adapted still further to anchor the armouring in relation to the body.

40 Advantageously the lamp is, at the rear, formed with a short rearwardly extending neck, and the armouring may be continued along the exterior of this neck and may terminate with the flange which assumes a position contiguous to the rear face of the said neck.

45 The armouring may be applied to the body by deposition as, for instance, by electro- 50 deposition or it may be applied by another

method of deposition as, for instance, by spraying the molten metal on the body.

In the case of electro-deposition, the body 55 may first be silvered or otherwise coated with a film of metal, or treated with a conducting metallic paint, that part of the body to which the armouring is to be applied being treated in this way so that the body can then be immersed in its entity in the electrolytic vat with the result that the armouring 60 is applied only to that part of the surface at which it is required.

The body having this integral front may be manufactured by blowing, moulding, or 65 other suitable process.

In order that this invention may be clearly understood and readily carried into practice, reference may be had to the appended sheet of explanatory drawings, on which—

70 Figure 1 is a sectional elevation of a lamp body according to the present invention.

75 Figure 2 is a side elevation of one form of support for a lamp body such as shown in Figure 1.

Figure 3 is an end elevation of the support shown in Figure 2.

80 In a convenient embodiment of the present invention as shown in the drawings, *a* represents the glass lamp body closed integrally at the front *b* and having an integral boss *c* at the rear. Over this body 85 an armouring *d* of metal is provided, as for instance by electro-deposition and the said armouring may be inturned at *d*¹ and flanged at *d*² so that it is effectually retained in relation to the glass body. The said armouring 90 may be covered with a layer of suitable paint *e*. Below the said armouring, that is to say between the latter and the glass, silvering may, if desired, be incorporated in 95 any appropriate manner to function as a reflector. It will be noted that a lamp body thus constructed can readily be cleansed internally without in any way impairing the silvering.

100 Such a lamp body may be mounted in any appropriate support. One suitable form of support is shown in Figures 2 and 3 in which a standard *f* carries an integral boss *g* which is formed with a flanged disc *h* adapted to receive the boss *c* of the lamp body. *i* is a contractile ring of channel section 105 which may be secured around the part *h* to retain the boss *c* therein. The boss *g* may also be of a contractile character and adapt- 110

ed to be clamped around the lamp holder, as for instance by a tightening screw passing through lugs g^1 shown in Figure 3.

Having described my invention what I claim and desire to secure by Letters Patent is:—

A reflecting lamp body for use on vehicles, said body being composed of glass or other frangible and substantially transparent material and having an integral closed front and further provided on its exterior surface with a coating of reflecting material, and also provided with a splinter confining

armor coating applied exteriorly of said reflecting coating by deposition, said armor coating terminating in a flange which extends inwardly and around the front to serve as an abutment to prevent rearward derangement of the armor coating and being also extended inwardly at the rear in order to anchor the armor coating in relation to the lamp body and prevent forward derangement of said coating.

In witness whereof I have hereunto set my hand.

C. E. GOODYEAR.
